UNITED STATES PATENT OFFICE

126,228

DESIGN FOR A RACK FOR A REFRIGERATOR, OVEN, OR THE LIKE

Leonard A. Young, Detroit, Mich.

Application November 16, 1940, Serial No. 96,626

Term of patent 14 years

To all whom it may concern:

Be it known that I, Leonard A. Young, a citizen of the United States, residing at Detroit, in the county of Wayne and State of Michigan, have invented a new, original, and ornamental Design for a Rack for a Refrigerator, Oven or the like, of which the following is a specification, reference being had to the accompanying drawing, forming part thereof, wherein:

Fig. 1 is a top plain view of a rack for a refrigerator, oven, or the like, showing my new design;

Fig. 2 is an enlarged end elevational view thereof, shown partly broken away; and

Fig. 3 is an enlarged sectional view, shown partly broken away, taken along and in the direction of the arrows of line 3—3 of Fig. 1.

I claim:

The ornamental design for a rack for a refrigerator, oven, or the like, as shown.

LEONARD A. YOUNG.
